UNITED STATES PATENT OFFICE

2,541,450

VIBRATOR INTERRUPTER

Richard M. Voyles, Indianapolis, Ind., assignor,
by mesne assignments, to Cornell-Dubilier Electric Corporation, South Plainfield, N. J., a corporation of Delaware

Application August 9, 1946, Serial No. 689,459

2 Claims. (Cl. 200—90)

1

My invention relates to improvements in electromagnetic vibrator interrupters, and more particularly to that type of vibratory interrupter adapted to open and close electrical contacts and which includes a vibratory member or reed carrying contacts which are rapidly opened and closed during the vibration of the reed.

It has for one of its objects the provision of a structure which, by means of a single vibrating structure, a two phase alternating current may be developed.

Another object of the invention is to provide a vibrating structure by which a high frequency alternating current may be developed by a vibrator operating at a relatively low frequency.

In one embodiment of my invention, a vibrating reed actuates four pairs (or a multiple thereof) of electrical contacts so that each pair closes and opens once during each cycle of the vibrating reed, provision being made so that the duration of contacts of all pairs of contacts is essentially equal and that the pairs close and open in succession at intervals substantially equal to one-fourth of a cycle of the vibrating reed, with the order of closing and opening being the same in all cycles.

Other objects and advantages of my invention will more fully appear in the accompanying specification and claims.

For the purpose of disclosing my invention, I have illustrated an embodiment thereof in the accompanying drawings, in which:

Fig. 1 is a side elevation of a vibrator embodying my invention;

Fig. 2 is a side elevation, looking in the opposite direction from Fig. 1;

Fig. 3 is a front elevation of a vibrator embodying my invention;

Fig. 4 is a diagrammatic view of a circuit, in which my vibrator may be used; and

Figs. 5, 6, 7, and 8 are graphs, illustrating the relative movements of the contact carrying parts.

In the embodiment illustrated, I provide a frame 1 on which the component parts of the vibrator are mounted. This frame at its upper end is provided with a transversely extending arm 2 to which is secured the driving magnet 3. A center reed 4 carrying an armature 5 influenced by the magnet 3 is supported between a pair of suitable insulating blocks 6 and 7 and comprising a vibrating driving means for the contact fingers connected thereto. This center reed has attached thereto two compliant center reed contact fingers 8 and 9 disposed on the opposite faces of the reed and each of these contact

2

fingers carries a contact 10 and comprising compliant means connecting the contacts with the center reed. The center reed also carries a pair of stiff center reed contact fingers 11 and 12, each carrying a contact 13, the contact fingers 11 and 12 being disposed on opposite faces of the center reed 4 the fingers 11 and 12 thus provide non-compliant means carried thereby with the center reed. Cooperating with the stiff contact carrying fingers 11 and 12 is a pair of compliant, relatively stationary contact arms 14 and 15, each carrying a contact 16 and comprising compliant contact supporting means, and cooperating with the compliant contact fingers 8 and 9 is a pair of relatively stationary, stiff contact arms 17 and 18, each carrying a contact 19 and comprising substantially rigid supporting means for the contacts carried thereby.

The relatively stationary contact compliant arms 14 and 15 and the relatively stationary stiff contact arms 17 and 18 are clamped between the insulating blocks 6 and 7 and insulating blocks 20 and 21, the whole assembly being secured to the lower end of the frame 1 by suitable clamping bolts 22. In addition to the above contacts, the center reed 4 also carries a driving contact arm 23 carrying a driving contact 24 adapted to engage a contact mounted on the driving contact post 25 bolted or otherwise secured to the frame 1, the arrangement being such that when the reed 4 is in its neutral position, the contact arm 24 is in engagement with the contact on the post 25, thereby closing the circuit through the driving magnet 3. As soon, however, as the driving magnet 3 is energized, it causes the armature 5 to move in a direction to move the center reed and with it the driving contact 24 in a direction to open the contact between the driving magnet 24 and the contact on the post 25, thus opening the circuit of the driving magnet. Upon the opening of the circuit of the driving magnet, however, the center reed will of course swing back in the opposite direction, after it has completed its driven movement, thus closing the circuit of the driving magnet, and in this manner, the vibration of the center reed is accomplished.

It is to be noted that there is one compliant finger and one stiff finger on each side of the plane of the center reed and that each compliant finger is paired with a stiff side arm or vice versa. The compliant fingers and side arms have a resonant frequency essentially equal to that of the whole vibrating structure.

In the graph illustrated in Fig. 5, the heavy line 26 shows the center reed and stiff finger dis-

placement relatively to the frame, while the lighter line 27 represents the velocity of the center reed relatively to the frame.

In Fig. 6, the heavy line 28 indicates the compliant finger displacement relative to the center reed and the lighter line 29 indicates the compliant finger velocity relative to the center reed.

In the graph illustrated in Fig. 7, the heavy line 30 denotes the compliant finger displacement relative to the frame, while the lighter line 31 represents the velocity of the compliant finger relative to the frame, the dotted lines indicating the effect of the making of contact of the compliant finger with the stiff side arm.

In the graph shown in Fig. 8, the heavy line 32 indicates the displacement of the compliant side arm with respect to the frame, while the lighter line 33 indicates the compliant side arm velocity relative to the frame, the dotted lines in this graph indicating the effect of the making of contact by a compliant side arm with a stiff contact finger on the reed.

In the circuit arrangement illustrated in Fig. 4, I have shown one application of my invention in a circuit for developing a single phase alternating current at twice the frequency of the center reed. In this circuit arrangement, the primary winding of a transformer 34 has a center tap connected to a source 35 of direct current supply. This source may be in the form of a battery. One of the outer terminals of the primary winding is connected to the oppositely disposed compliant contact arms 14 and 15, while the opposite outer terminal of the primary winding 34 is connected to the oppositely disposed stiff side arms 17 and 18. The center reed 4 is connected to the opposite terminal of the battery 35. The driving magnet 3 has one terminal connected to the battery 35, while the opposite terminal is connected to the stationary post 25 normally in contact with the contact 24.

It must be understood that while the center reed is stationary and therefore, in its neutral position, no contact is made between the various contacts of the vibrating interrupter (except of course the driving magnet contacts). With the center reed vibrating, there is a certain amount of vibratory movement imparted to the compliant side arms, as a result of the impact of the stiff fingers with these side arms, and likewise there is a certain amount of vibratory movement set up in the compliant fingers, as a result of their impact during the vibratory movement of the center reed, with the stiff side arms, their primary movement however, being imparted by the movement of the center reed. Therefore, the contact is made and broken at approximately the neutral position of the vibratory reed during operation.

In operation, assuming that the center reed is vibrating and, assuming for the purpose of illustration, that the center reed 4 is moving in the direction of the arrow, Figs. 1 and 2, the stiff fingers 12 will move in phase with the center reed 4 making contact with the flexible side arm 15, when the center reed 4 is approximately in its neutral position (time A, Fig. 7). It must be borne in mind that as a result of the contacts between the stiff side fingers with the compliant side arms, vibration has also been set up in the side arm 15 and, as a result of this vibration, the side arm 15 has moved in the direction of the arrow past its neutral position. Accordingly, the engagement of the stiff finger 12 with the compliant side arm 15 is approximately at the neutral

75

position of the center reed 4. At this instant of contact, the flexible side arm towards which the center reed is moving is in its position of maximum displacement, during its vibratory movement, towards the center reed. One-fourth of a cycle later (time B, Fig. 7), the center reed 4 and consequently the stiff finger 12 is in the position of extreme displacement and its velocity is zero, while the flexible side arm 15 with which the stiff finger 12 is in contact is in its position of zero displacement and maximum velocity away from the center reed. At this instant, with the center reed 4 reversing its movement, the contact will be broken.

Meanwhile, when the center reed 4 is approximately in the neutral position (time A, Fig. 7), the compliant finger 9, lagging the center reed by one-fourth of a cycle, is in a position of maximum displacement relative to the center reed toward the center reed. One-fourth of a cycle later (time B, Fig. 7), the compliant finger 9 is in a position of neutral displacement relative to the center reed and maximum velocity away from the center reed, while the center reed is at maximum displacement and zero velocity, relative to the frame and the stiff side arms. At this instant, which is essentially the same instant as when the stiff finger breaks contact with the compliant side arm, the compliant finger 9 will make contact with the stiff side arm 18. After another one-fourth cycle (time C, Fig. 7), the center reed will be approximately in its neutral position, the compliant finger 9 will have zero velocity relative to the center reed and will have a velocity relative to the stiff side arm. Accordingly, at this instant, contact between the contacts on the compliant arm 9 and stiff arm 18 will be broken.

At approximately this instant (time C, Fig. 7), the stiff finger 11 on the opposite side of the plane of the center reed will contact the contact on the compliant side arm 14, breaking contact approximately one-fourth of a cycle later (time D, Fig. 7), at which time the contact on the adjacent compliant finger 8 will engage the stiff side arm 17. Finally, at the end of a full cycle (time A', Fig. 7), the compliant finger will break contact with the contact on its stiff side arm and the cycle will be repeated.

Accordingly, referring to Fig. 4, when the reed 4 is moved in the "up" position, stiff side arm 12 will first make contact with the contact on the compliant side arm 15 closing the circuit in one direction through the upper half of the primary 34. One-fourth of a cycle later, compliant finger 9 will make contact with the stiff side arm 18, closing the circuit in the opposite direction through the lower half of the primary winding 34, and on the down-swing, substantially the same reversal will occur, thereby delivering through the transformer a two phase alternating current at the frequency of the vibrating reed.

I claim as my invention:

1. In a vibrating device, a vibrating reed, a pair of compliant contact fingers supported on the opposite faces of said reed, and a pair of non-compliant contact carrying arms disposed on the opposite sides of said reed and between which said compliant contact fingers operate, a pair of non-compliant contact fingers supported on the opposite faces of said reed and a pair of compliant contact supporting arms disposed on the opposite sides of said vibrating reed and cooperating with said non-compliant contact carrying fingers supported on said reed.
2. In a vibrating device, a vibrating reed, a pair

of compliant contact fingers supported on the opposite faces of said reed and a pair of non-compliant contact carrying arms disposed on the opposite sides of said reed and between which said compliant fingers operate, a pair of non-compliant contact fingers supported on the opposite faces of said reed and a pair of compliant contact supporting arms disposed on the opposite sides of said vibrating reed and cooperating with said non-compliant contact carrying fingers supported on said reed, a driving magnet for said reed, and means controlling said reed for effecting an intermediate energization of said magnet.
